V. Z. CARACRIST'.
APPARATUS FOR FEEDING POWDERED FUEL.
APPLICATION FILED MAY 25, 1914.

Patented Nov. 24, 1914.

UNITED STATES PATENT OFFICE.

VIRGINIUS Z. CARACRISTI, OF ALBANY, NEW YORK.

APPARATUS FOR FEEDING PULVERIZED FUEL.

1,118,634.

Specification of Letters Patent.

Patented Nov. 24, 1914.

Application filed May 25, 1914. Serial No. 840,842.

To all whom it may concern:

Be it known that I, VIRGINIUS Z. CARACRISTI, a citizen of the United States of America, and resident of Albany, in the county of Albany and State of New York, have invented certain new and useful Improvements in Apparatus for Feeding Pulverized Fuel, of which the following is a specification.

The object of this invention is to provide an apparatus whereby pulverized fuel, such as fine coal—commonly called breeze, or other material of like powdered nature, may be advantageously and thoroughly mixed with the quantity of air required for the combustion of the same, and the mixture delivered in form suitable for use as fuel for all those purposes for which pulverized fuel is adapted. For this purpose means are provided that produce a hollow cylindrical stream or envelop of air at both the outside and the inside of which the pulverized fuel is fed, said fuel being taken up by the stream of air in its passage toward the nozzle from which both are delivered.

In the accompanying drawing, Figure 1 is a vertical longitudinal section of an apparatus embodying the invention, and Fig. 2 is a vertical transverse section on line 2—2, Fig. 1.

Similar reference numerals indicate corresponding parts in both figures.

Referring to the drawing, and more particularly to Fig. 1, the apparatus comprises a casing supported in any suitable manner, and consisting of a front portion 10 and a vertical rear-portion or fuel-box 11 connected therewith. Within this front-portion 10 is arranged a hollow rotary return screw 12, said return screw being mounted in the casing, as shown at 13, 14, so as to rotate freely therein, a space 10^a being left free to prevent unnecessary friction. Within said hollow return screw 12 is located the annular nozzle 15 of an air supply-pipe 16 which is arranged at the rear of the casing 10. Within the hollow nozzle 15 is located a fuel feed-screw 17. The feed-screw is driven by gear and pinion connections 18 and 19, 20 and 21, from an electric motor 22 or other suitable source of power. At the lower part of the portion 10 is mounted a shaft 23, which carries the pinion 19. Said shaft also carries a pinion 24 which meshes with teeth 25 at the forward-end of the return screw 12. The diameter of said pinion

19 and the gear 18, and the diameter of said pinion 24 and the gearing 25 are substantially the same, but may be changed depending upon the various relative speeds desired to be given to the parts. Hence, the return screw 12 and the feed-screw 17 are driven in the same direction, as is clear from an examination of Fig. 1. A nozzle 26 is connected with the casing 10, and extends over and closes the forward end of the return screw 12. To the discharge end of the nozzle 26 is connected a pipe 27 for carrying off the mixed fuel. A packing 28, between the return screw and the casing 10, renders the connection between these parts tight at that point. A spring-actuated washer 29 between the nozzle 26 and the return screw 12 makes a tight connection at the forward-end of the return screw.

The pulverized coal is fed through a supply-pipe or hopper 30 into the fuel-box 11, which has an inclined guide wall 30^a, and the fuel falls in contact with the feed-screw 17, which extends through the lower part of the hopper or fuel-box 30. The screw 17 has its discharge end in proximity to the discharge end of the air nozzle 15, and the air nozzle 15 is arranged around the discharge end of the feed screw. The air nozzle 15 is located at a considerable distance back from the outer end of the return screw 12, as shown in the drawing, and approximately on the vertical plane of the tip of said air nozzle, said return screw begins to contract toward the main nozzle 26 of the apparatus with which the inner wall-surfaces of said return screw form practically a continuation, the nozzle 26 being enlarged at its inner portion 32 so as to meet the contracted portion 33 at the outer end of the return screw. The helical rib 31 is continued, namely, beyond the delivery-end of the air-nozzle 15. There is thereby formed in the forward portion of the return screw 10 and the enlarged portion of the main nozzle 26, a space which is used as a mixing space, in which the fuel is fed by the air nozzle, the said column of air issuing from the air nozzle 15. In the embodiment shown in the drawing this column of air is cylindrical and hollow. In the event of any difficulty in casting the air-nozzle as shown in the embodiment shown in the drawing, and if it is desired for structural reasons to put any insertions in the air nozzle, it may be that these insertions will impede somewhat the

flow of the air therethrough, but it will be found that the air will form itself into the hollow nozzle after a short distance, and will issue substantially in the form of a hollow column from the air nozzle. The diameter of the air nozzle is greater than that of the mouth 37 of the main nozzle 26, but is less than that of the enlarged rear portion of said nozzle. The result of this construction is that the stream or envelop of air now carrying fuel strikes against the rear portion of the nozzle 26 and is deflected thereby, and the stream contracted to a reduced diameter, the particles of fuel carried by the same being deflected toward the center of the stream, and a mixture of uniform density, and having increased lineal speed over that of the air discharged from the air nozzle 15, is produced and discharged through the mouth 37 of the main nozzle 27.

The pitch of the screw 17 is opposite to that of the return screw 12, and the feed screw 17 feeds the fuel forwardly, discharging it at the end 17^a. As it is discharged, the fuel is continually enveloped by the envelop of air discharged from the nozzle 15 at 15^a. As the fuel drops, portions of it are carried forward, and are delivered into the mouth 37, all the time being commingled with air. Other portions which are not conveyed by the first action of the air stream, drop by gravity into the spaces 31^a, 31^b, 31^c, and by so dropping, pass through the envelop of air, and are thus intimately mixed with the air. As so mixed, they drop on to the return screw 12, and are conveyed in a rotary direction by the rotation of the return screw. When it reaches a point where it is free to drop away from the return screw 12, it falls down again on to the outer portion of the envelop, and through the envelop of air, and then again commingles with the incoming fuel, and at the same time that portion not conveyed by the air stream from the air nozzle to the mouth 37, drops through the lower portion of the envelop of air, and again on to the wall of the return screw, probably into the spaces 31^a, 31^b, 31^c, and also into a portion closer to the nozzle. A certain portion, however, of this air-enveloped fuel, which was conveyed upwardly by the return screw, is conveyed by the stream outwardly to the nozzle 27. As this action is repeated, the fuel in the mixing chamber, formed by the outer portion of the return screw, the end of the air nozzle, and the discharge of the feed screw, is recurrently brought into contact with the air, and thereby a thorough intermixing of the fuel and air takes place. Certain portions of this fuel which are not fed forwardly into the mouth 37 and nozzle 27, are conveyed rearwardly by the return screw 12 into the space 12^a beyond the action of the air column, and are then carried

by the rotary action of the return screw, and conveyed rearwardly to the space 31^a, which is formed by the rear end of the return screw, the rear end of the air nozzle, the feed screw, and by the deflecting plate 13^a. Here the fuel has an opportunity of again being carried forward by the fuel feed screw 17, and may then be again subjected to the operation of the air envelop as described. Whatever surplus fuel is not fed by the screw 17 forwardly, passes through the space 30^b, into the feed hopper 11. It may then be fed by the feed screw 17 as the action may require. In the event of a failure of the air blast issuing from the nozzle, the return screw will return all the fuel thereby preventing a choking at the mouth 37.

In the embodiment shown in Fig. 1, the nozzle has been shown to have its discharge end substantially in line with the discharge end of the feed screw, but it is clear that changes may be made herein, in that the feed screw may extend beyond the discharge end of the nozzle 15^a, or the nozzle may terminate somewhat rearwardly of the position shown in Fig. 1.

The apparatus described produces economically a fuel mixture extremely rich in the elements of combustion. By reason of the hollow stream of air and the supply of fuel, the recurrent mixing of the elements is thoroughly accomplished.

One embodiment of the invention has been described, but it is obvious that changes may be made therein without departing from the spirit of the invention as set forth in the claims, especially in so far as relates to any of the mechanical features which have been described and enter into an operative device.

I claim:

1. An apparatus for feeding pulverized fuel, comprising a feeding element for supplying fuel, and an air nozzle arranged around the feeding element, adapted to supply a hollow column of air to the fuel, and a conveyer around the feeding element and nozzle for recurrently feeding to the column of air the fuel, and returning certain portions of the fuel to the feeding element.

115

2. An apparatus for feeding pulverized fuel, comprising a feed screw for supplying fuel, an air nozzle arranged around the feed screw at the discharge end thereof, a return screw arranged around the feed screw and the air nozzle, and extending forwardly of the feed screw and air nozzle, forming a mixing chamber at the front of the feed screw and air nozzle.

120

3. An apparatus for feeding pulverized fuel, comprising a feed screw for supplying fuel, an air nozzle arranged around the feed screw at the discharge end thereof, a return screw arranged around the feed screw and the air nozzle, and extending forwardly of

125

130

the feed screw and air nozzle, forming a mixing chamber at the front of the feed screw and air nozzle, and a fuel chamber at the rear of the air nozzle and return screw and adjacent the feeding portion of the feed screw.

In testimony, that I claim the foregoing

as my invention, I have signed my name in presence of two subscribing witnesses.

VIRGINIUS Z. CARACRISTI.
